VENDING MACHINE CABINET

Walter L. Koch, Caldwell, Robert P. Franklin, Jefferson Township, and George R. Huyler, Hanover, N.J., assignors to Rowe International, Inc., Whippny, N.J.

Filed Apr. 1, 1970, Ser. No. 22,165

Term of patent 14 years

Int. Cl. D20—01

U.S. Cl. D52—3

FIG. 1 is a front elevation of a vending machine cabinet showing our new design.

FIG. 2 is a left side elevation thereof, the other side being a mirror image.

FIG. 3 is a top plan view thereof.

The rear of the vending machine cabinet is plain and unornamented.

We claim:

The ornamental design for a vending machine cabinet, substantially as shown and described.
